United States Patent Office

Des. 203,422
Patented Jan. 4, 1966

203,422

TRASH RECEPTACLE OR SIMILAR ARTICLE

Don Taylor Dean, 810 Borger St., Plainview, Tex.

Filed Feb. 25, 1965, Ser. No. 83,984

Term of patent 14 years

(Cl. D58—17)

FIG. 1

FIG. 7

FIG. 2

FIG. 3

FIG. 5

FIG. 4

FIG. 6

FIG. 1 is a perspective view of a trash receptacle or similar article showing my new design;

FIG. 2 is a top view thereof;

FIG. 3 is a back view thereof;

FIG. 4 is a front view thereof;

FIG. 5 is a sectional view thereof taken substantially on line 5-5 of FIG. 4;

FIG. 6 is a bottom view thereof; and

FIG. 7 is a side view thereof.

I claim:

The ornamental design for a trash receptacle or similar article, as shown.
